METHOD OF AND APPARATUS FOR TREATING MOHAIR, WOOL, AND THE LIKE

Application filed February 5, 1931. Serial No. 513,663.

My invention relates to improvements in the method of and apparatus for treating mohair, wool, cotton and like material, specifically in the method of and apparatus for opening, dusting, sorting, weighing and/or storing said mohair or like material.

It has been the practice in the art in sorting mohair to have a skilled mohair sorter do a lot of manual labor which can be readily done by unskilled labor in the actual sorting of the mohair. The skilled mohair sorter takes the original material whether it be directly from the bale or from a suitable receptacle therefor and places it in front of him on a single large board table. He then individually takes the mohair and selectively sorts out the qualities into piles. The skilled laborer then must transfer the piles into proper receptacles and move them to the desired place for further treating of the selected grades of mohair. I have realized therefore that it is possible to substitute a large amount of the manual labor done by these skilled mohair sorters by unskilled labor at a relatively less price and also to appreciably lessen the amount of labor necessary in the handling and transmission of the mohair. To this end I provide a continuously moving perforated, preferably woven wire conveyor having a surface thereof moving in a substantially horizontal plane. I provide means such as modified picker means to open up and feed a substantially even preferably relatively thin layer of material on said continuously advancing conveyor surface. In order to remove dust and other minor impurities which come with the mohair therefrom, I provide means to continuously draw a gaseous stream through said continuously moving layer of material and surface to remove dust and other small impurities therefrom.

Whereas in the prior art each individual mohair sorter has had to continuously pick over the mohair in front of him which is in the form of a pile to select the different qualities therefrom, I have found that by spreading out the mohair in a relatively even layer in a continuously moving stream the sorting may be more readily accomplished. In addition to this I have divided the stream of

mohair into so-called zones, and provided stands for sorters at spaced points along said conveyor for a sorter to stand at the most convenient height for sorting, adjacent said moving stream, and I provide receptacles such as bins or removable baskets spaced at correspondingly predetermined distances along said conveyor, each adapted to receive a different class of graded qualities from said main stream. I thus divide the conveyor into zones and in each zone I place an individual sorter, whose sole duty is to remove a specified grade or quality and throw it into the receptacle opposite him. I thus therefore by feeding the mohair in an even stream make it much easier for the sorter to sort, and I thus educate single sorters to look for a single quality and become more efficient in the sorting out of that one quality from the substantially small layer of original material, than said sorter would be in sorting out a large plurality of different qualities and continuously picking over the mohair in the pile in front of him. I thus in a manner substantially revolutionize the present-day sorting of mohair by first spreading the mohair out on a continuously moving conveyor in a thin layer so that all types of qualities may be readily seen by the sorters without picking over piles in front of them and secondly I educate individual sorters so as to look for single classes or grades and thereby enable each individual sorter to become more proficient in the sorting of his specific quality.

It is apparent that in place of treating mohair, other fibres, such as wool, cotton, etc., waste, rags, or any other suitable type of similar products may be similarly treated.

While the usual bale of mohair contains a certain amount of grades most of the mohair will come through of a single grade and thus in one embodiment of my improved apparatus and process, there emerges from the end of the conveyor a single grade of sorted mohair or like material, and on each side of the conveyor are receptacles, each containing an expertly sorted single class or grade which may be added to other groups to make up a

sufficiently large standard grade for its individual later treatment.

Further objects of my invention relate to the substantially automatic moving of the mohair or other material while it is being 5 dusted, opened, sorted and weighed. I thus may drop the mohair from one floor into the picker, have it automatically moved from the picker on to the conveyor, have it automatically moved from the conveyor on to a 10 weighing machine and having it automatically moved from the weighing machine into storage bins on a lower floor.

A further object of my invention is to provide means to automatically weigh the sorted 15 stream of material.

A further object of my invention is to provide an apparatus in which the speed of the conveyor may be readily regulated for different classes, kinds, grades, or material so 20 as to run the conveyor at the most efficient speed for the most efficient selective sorting thereof.

These and such other objects of my invention as may hereinafter appear will be best 25 understood from a description of the accompanying drawings which illustrate an embodiment thereof.

In the drawings, Fig. 1 and Fig. 1^a, broken 30 between Figs. 1 and 1^a for lack of space in the sheet represent a side elevation, partly shown in section of an embodiment of my invention mounted for most efficient automatic handling of the material on three different floors of a factory.

Figs. 2 and 2^a are corresponding diagrammatic plan views thereof, the individual floors having been removed.

Fig. 3 is a vertical sectional view looking 40 towards the feeding end of the conveyor taken along the line 3—3 of Fig. 1.

Fig. 4 is a longitudinal sectional view of the feeding end of the conveyor taken along the broken line 4—4 of Fig. 2.

In the drawings, wherein like characters 45 of reference indicate like parts throughout, generally indicates a continuously moving surface constructed in accordance with my invention.

In the preferred embodiment shown, said 50 moving surface 10 preferably includes the upper surface of a continuously moving conveyor 12 preferably perforated as at 14, preferably by being made of spaced woven wire 55 moving in a substantially horizontal plane. In the embodiment shown, the conveyor 12 comprises a continuous moving conveyor revolving around the drums 16 and 18. As shown in Fig. 2^a the drum 18 is suitably 60 driven through the medium of the gearing 20 which is suitably driven by means of the step-up pulley 22 so that the speed of the conveyor may be adjustably varied.

I provide means to open up and feed a substantially even layer of material on said con-

tinuously advancing upper surface 10. In my preferred embodiment, said means comprises a modified type of picker means, such as is used in opening up cotton and animal fibres.

In the preferred embodiment shown for convenience of automatic handling to dispense with the amount of unskilled labor formerly thought necessary my invention is preferably constructed on three floors. The upper floor A is provided with a chute 24 through which the original unbaled material is led into the picker means 26. Said picker means includes a usual horizontal conveyor 28, a continuously revolving oblique conveyor 30 provided either with card clothing or suitable material to pick up even layers of mohair or other material thereon and a suitable doffing comb 34 to keep the material caught on the card clothing or other projections in a thin even layer across the upwardly moving material advancing surface 36 of said conveyor 30. The material from said conveyor may then be dropped on another oblique delivery belt 38 and dropped from there in a substantially even layer 40 on the continuously moving conveyor 10. It is thus apparent that the mohair or other material will be fed in a substantially even layer 40 on the upper surface 10 of the continuously moving conveyor 12.

I provide means to continuously draw a gaseous stream preferably downward through the continuously moving layer 40 of material and surface 10 to remove dust, or other small impurities therefrom. While any suitable type of means may be provided for this purpose, I preferably provide the suction fan 42 suitably connected by the pipe 44 which is individually connected at spaced intervals by means of the pipes 46 to the troughs 48 which extend at spaced intervals underneath the upper surface of the conveyor 12 so that each end thereof will be substantially adjacent to provide a substantially continuous suction along the entire surface of the material being treated. The pipe 44 may be also connected by means of the pipe 50 to the picker apparatus to remove floating dust particles therefrom in addition. A suitable waste discharge pipe 52 leads from the suction fan to discharge the waste in any suitable place.

The entire conveyor is thus located on the floor B and I provide means to continuously weigh the graded stream of material 40 after it has been discharged from the conveyor 10. The storage bins 54 for said graded stream of material are preferably placed on a lower floor C and means are provided to continuously lead said graded stream of material to said storage bins. The weighing apparatus 56 is preferably located intermediate the said floors B and C in said factory, extending through the floor B. Automatic weighing

machines are well known in the art and I may insert one of any standard type. Said machine comprises a hopper 58 adapted when it has been filled to the desired amount to automatically open up and discharge into the exhaust pipe 60 below it. The hopper 58 will thus discharge when the predetermined amount of material has been put therein and will immediately close up, thereby permitting a continuous automatic weighing of the stream of sorted material. The pipe 60 leads to the respective storage bins 54 and for ease of moving the material may be provided with a pressure fan 62. I employ the word storage bin, however, to include any type of permanent or movable storage receptacle. In order to remove the material from the discharge end of the conveyor 12 I provide a suitable delivery belt 64 which as shown is arranged at an oblique angle to lead the continuous stream of sorted and graded material 40 from the discharge end of the conveyor and drop it into the hopper 58 of the weighing machine 56.

As stated, a main feature of my invention consists of selectively separating the various classes or grades from the main thin layer or stream of mohair or other material at spaced points along said stream or conveyor, whereby said sorted stream may consist entirely of graded material and said classified qualities may form standard grades of material of different classes from that of the main stream. For this purpose I provide receptacles arranged at predetermined distances along one side of said conveyor, each adapted to receive a different class or quality from said main stream. I thus in the embodiment shown divide the space along the conveyor in five zones, namely, *a*, *b*, *c*, *d*, and *e* and I place the receptacles 64^a, 64^b, 64^c, 64^d and 64^e respectively along and opposite each respective zone adjacent one side of the conveyor. I provide stands 66^a, 66^b, 66^c, 66^d and 66^e spaced along the opposite side of said conveyor at corresponding predetermined distances corresponding to the receptacles 64^a, 64^b, 64^c, 64^d and 64^e. In the preferred embodiment said stands comprise sections of the floor B and are spaced below the upper surface of the conveyor a suitable height for the efficient working of the sorters working over the zones *a*, *b*, *c*, *d* and *e* of the conveyor, in the preferred embodiment shown for most efficient sorting being substantially half the height of a man. It is thus obvious that a sorter will be provided for each zone, standing respectively on the stands 66^a, 66^b, 66^c, 66^d and 66^e and each sorter will sort a single class or grade out from the main stream and throw them into the receptacles 64^a, 64^b, 64^c, 64^d and 64^e respectively on the opposite side of the conveyor. It is thus obvious that by providing a sorter to sort out a single type or grade from the main stream that he will

become more proficient in the individual job of looking for single types or grades in a substantially thin main stream than was heretofore possible where sorters were sorting all types or grades from a pile of mohair.

It is obvious that the conveyor 12 will be of such a width, that the sorter can readily reach for any type or quality on the furthermost side of the conveyor from him and that each individual zone or section will be of a width that a man or sorter standing in the center of each stand 66^a may readily reach all material passing by him with his right or left hand. It is thus obvious that I have provided a novel apparatus for, and method of obtaining standard grades of mohair or like material and in which the entire time of the expert mohair or other sorters is employed in actual sorting, in which they are required to do practically no unskilled labor, in which the amount of handling is materially reduced and in which unskilled labor may be employed to open up the material into the picker means and to remove the material from the storage bins and move the receptacles to the desired place, leaving the skilled mohair or other sorter free to devote his entire time to the actual sorting operation and as an individual sorter is continuously employed for sorting one type of material enable him to become more efficient in the particular task. While my invention is particularly adapted for sorting, dusting, opening up and weighing fibers, it is obvious that it may be readily employed for use in sorting rags, waste and similar products.

It is understood that my invention is not limited to the specific embodiment shown or method described and that various deviations may be made therefrom without departing from the spirit and scope of the appended claims.

What I claim is:

1. In a machine for obtaining standard grades of mohair or like material, in combination, a continuously moving woven wire conveyor having the upper surface thereof moving in a substantially horizontal plane, means to open up and feed a substantially even relatively thin layer of material on said continuously advancing upper surface to form a continuously advancing main stream of material, means to continuously draw a gaseous stream downwards through said continuously moving layer of material and surface to remove dust and other small impurities therefrom, receptacles spaced at predetermined distances along said conveyor each adapted to receive a different class of graded qualities from said main stream, stands spaced along the opposite side of said conveyor at corresponding predetermined distances spaced below said surface, means to continuously weigh the graded stream of

material, storage bins for said graded material and means to continuously lead said graded stream of material to said storage bins.

5 2. In a machine for obtaining standard
grades of mohair or like material, in
combination, a continuously moving perforate
surface, means to feed a substantially even
10 relatively thin layer of material on said
continuously advancing surface to form a
continuously advancing main stream of
material, means to continuously draw
a gaseous stream through said continuous-
ly moving layer of material and surface
15 to remove dust and other small impuri-
ties therefrom, receptacles placed at pre-
determined distances along said conveyor,
each adapted to receive different graded qual-
ities from said main stream and stands
20 placed along the opposite side of said surface
at corresponding predetermined distances
spaced below said surface and means to con-
tinuously weigh the graded stream of ma-
terial.

25 3. In a machine for obtaining standard
grades of mohair or like material, in com-
bination, a continuously moving perforate
surface, means to feed a substantially even
30 relatively thin layer of material on said con-
tinuously advancing surface to form a con-
tinuously advancing main stream of ma-
terial, receptacles spaced at predetermined
35 distances along said conveyor each adapted
to receive different graded qualities from
said main stream and stands spaced along
the opposite side of said surface at corre-
sponding predetermined distances spaced
40 below said surface, storage bins for said
graded material and means to continuously
lead the said graded stream of material to
said storage bins.

4. In a machine for obtaining standard grades of mohair or like material, in combination, a continuously moving perforate surface, means to open up and feed a substantially even relatively thin layer of material on said continuously advancing surface to form a continuously advancing main stream of material, receptacles spaced at predetermined distances along said conveyor each adapted to receive different graded qualities from said main stream and stands spaced along the opposite side of said surface at corresponding predetermined distances spaced below said surface and means to continuously weigh said graded stream of material.

5. In a machine for obtaining standard grades of mohair or like material, in combination, a continuously moving perforate surface, means to open up and feed a substantially even relatively thin layer of material on said continuously advancing surface to form a continuously advancing main stream of material, means to continuously draw a gaseous stream through said continuously

moving layer of material and surface to remove dust and other small impurities therefrom, receptacles spaced at predetermined distances along said conveyor each adapted to receive different graded qualities from said main stream, stands spaced along the opposite side of said surface at corresponding predetermined distances spaced below said surface, storage bins for said graded material and means to continuously lead said graded stream of material to said storage bins.

6. In a machine for obtaining standard grades of mohair or like material, in combination, a continuously moving woven wire conveyor having the upper surface thereof moving in a substantially horizontal plane, means to open up and feed a substantially even relatively thin layer of material on said continuously advancing upper surface to form a continuously advancing main stream of material, means to continuously draw a gaseous stream downwards through said continuously moving layer of material and surface to remove dust and other small impurities therefrom, receptacles spaced at predetermined distances along said conveyor each adapted to receive a different class of graded qualities from said main stream, stands spaced along the opposite side of said conveyor at corresponding predetermined distances spaced below said surface and means to continuously weigh the graded stream of material.

7. In a machine for obtaining standard grades of mohair or like material, in combination, a continuously moving woven wire conveyor having the upper surface thereof moving in a substantially horizontal plane, means to open up and feed a substantially even relatively thin layer of material on said continuously advancing upper surface to form a continuously advancing main stream of material, means to continuously draw a gaseous stream downwards through said continuously moving layer of material and surface to remove dust and other small impurities therefrom, receptacles spaced at predetermined distances along said conveyor each adapted to receive different graded qualities from said main stream, stands placed along the opposite side of said conveyor at corresponding predetermined distances spaced below said surface, storage bins for said graded material and means to continuously lead said graded stream of material to said storage bins. 100 105 110 115 120

8. In a machine for obtaining standard grades of mohair or like material, in combination, a continuously moving woven wire conveyor having the upper surface thereof moving in a substantially horizontal plane, picker means to open up and feed a substantially even relatively thin layer of material on said continuously advancing upper surface to form a continuously advancing main 130

- stream of material, means to continuously draw a gaseous stream downwards through said continuously moving layer of material and surface to remove dust and other small 5 impurities therefrom, receptacles spaced at predetermined distances along said conveyor each adapted to receive a different class of graded qualities from said main stream, stands spaced along the opposite side of said 10 conveyor at corresponding predetermined distances spaced below said surface, means to continuously weigh the graded stream of material, storage bins for said graded material and means to continuously lead said 15 graded stream of material to said storage bins. 75
9. In a machine for obtaining standard grades of mohair or like material, in combination, a continuously moving woven wire conveyor having the upper surface thereof moving in a substantially horizontal plane, means to open up and feed a substantially even relatively thin layer of material on said continuously advancing upper surface to form a 20 continuously advancing main stream of material, means to continuously draw a gaseous stream downwards through said continuously moving layer of material and surface to remove dust and other small impurities therefrom, receptacles spaced at predetermined distances along said conveyor each adapted to receive a different class of graded qualities from said main stream, stands spaced along the opposite side of said conveyor at corresponding predetermined distances spaced below said surface, means to continuously weigh the graded stream of material, storage bins for said graded material, means to continuously lead said graded stream of material 25 to said storage bins and means for adjustably varying the speed of the conveyor. 80
10. A method of sorting mohair or like material which comprises spreading a substantially continuous layer of said material on a continuously moving perforate conveyor, continuously moving said conveyor and thin layer of said material to form a continuous moving thin stream of said material, passing a continuous supply of gaseous material 30 through said stream of moving material to remove dust and small impurities therefrom and selectively separating single graded classes of impurities from said moving stream at spaced fixed points relative to said moving stream, whereby said sorted stream may consist of graded material and said classified impurities may form separated standard grades of material of different classes from 35 that of the said stream. 85
11. A method of sorting mohair or like material which comprises spreading a layer of said material on a moving perforate conveyor, moving said conveyor and layer of said material to form a moving stream of said 40 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 90
12. A method of sorting mohair or like material which comprises spreading a layer of said material on a moving perforate conveyor, moving said conveyor and layer of said material to form a moving stream of said 45 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 95
13. A method of sorting mohair or like material which comprises spreading a layer of said material on a moving perforate conveyor, moving said conveyor and layer of said material to form a moving stream of said 50 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 100
14. A method of sorting mohair or like material which comprises spreading a layer of said material on a moving perforate conveyor, moving said conveyor and layer of said material to form a moving stream of said 55 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 105
15. A method of sorting mohair or like material which comprises spreading a layer of said material on a moving perforate conveyor, moving said conveyor and layer of said material to form a moving stream of said 60 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 110
16. A method of sorting mohair or like material which comprises spreading a layer of said material on a moving perforate conveyor, moving said conveyor and layer of said material to form a moving stream of said 65 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 115
17. A method of sorting mohair or like material which comprises spreading a layer of said material on a moving perforate conveyor, moving said conveyor and layer of said material to form a moving stream of said 70 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 120
18. A method of sorting mohair or like material which comprises spreading a layer of said material on a moving perforate conveyor, moving said conveyor and layer of said material to form a moving stream of said 75 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 125
19. A method of sorting mohair or like material which comprises spreading a layer of said material on a moving perforate conveyor, moving said conveyor and layer of said material to form a moving stream of said 80 material, passing a supply of gaseous material to said stream of moving material to remove dust and small impurities therefrom and selectively separating graded classes of impurities from said moving stream at spaced fixed points relative to said moving stream, whereby said sorted stream may consist of graded material and said classified impurities may form separated standard grades of material of different classes from that of the said stream. 130
